UNITED STATES PATENT OFFICE.

ERNEST C. RODWICK, OF UKIAH, CALIFORNIA.

MUFFLER.

1,110,512.

Specification of Letters Patent. Patented Sept. 15, 1914.

Application filed March 23, 1912. Serial No. 685,683.

To all whom it may concern:

Be it known that I, ERNEST C. RODWICK, a citizen of the United States, residing at Ukiah, in the county of Mendocino and State of California, have invented new and useful Improvements in Mufflers, of which the following is a specification.

This invention relates to mufflers and more particularly to a mute exhaust which can be applied to gas or steam engines.

The primary object of this invention is to provide a device of this character which is to be applied to the end of an exhaust pipe whereby when the exhaust gases come in contact therewith they can be divided up into such a state that they will break up and suppress the loud noises of the exhaust gases.

A further object of this invention is to provide a device of this character which will destroy the sound and at the same time prevent the back pressure of the engine without wasting the power thereof.

A further object of this invention is to provide a device of a few number of parts which will be easy to construct, cheap to manufacture, durable and efficient in use and which can be readily operated by the exhaust.

With the foregoing and other objects in view this invention consists of a novel construction, combination, formation and arrangement of parts as will be hereinafter more fully described, claimed and particularly pointed out in the drawings, in which,

Figure 1 is a side elevation of my improved muffler showing the parts thereof assembled. Fig. 2 is a vertical longitudinal section of the same. Fig. 3 is a side elevation of the inner tube having the outer chamber removed therefrom, and Fig. 4 is a section taken on the line 4, 4, of the Fig. 2 in the direction of the arrows as shown.

Referring now to the drawings wherein like references indicate similar parts throughout the several views, the letter A denotes generally my improved muffler which is applied to the end of an exhaust pipe B in the usual well known manner. This muffler consists of an inner cylindrical jacket which is preferably made of three sections 10, 11 and 12, these three sections being detachably secured together by means of threads 13 as more clearly shown in Fig. 2 of the drawings to facilitate and permit a detachment of the inner cylindrical casing in case the interior mechanism contained

therein should for any reason become inoperative or out of order. The first section 10 is provided with the threaded aperture 14 to receive the exhaust pipe B and journaled within the sections 10 and 12 is the convoluted cylindrical wheel 15 which also lies within the center section 11 and its purpose will be hereinafter more fully described. The wheel 15 is mounted in preferably ball bearing journals 16 which are mounted within each of the end sections 10 and 12 by means of radially extending arms 17. This convoluted wheel 15 is provided with radially extending blades 18 which are bent inwardly at their extremities as at 19 and lie at an angle to the axis of the wheel.

The central section 10 is provided with a plurality of elongated slots 20 through which the gases exhaust into the chamber 21, 75 which is formed by the cylindrical casing 22. This cylindrical casing is spaced from the inner jacket by means of radially extending arms 23 which are formed upon the members 10 and 12. The usual oil cups 24 30 are provided in each of the members 10 and 12 whereby suitable supply of oil will be furnished to the ball bearings, thereby facilitating the rotation of the convoluted wheel 15.

It is apparent from the aforesaid construction that when the gases in the exhaust pipe enter within the chamber formed in the section 10 they come in contact with the convoluted wheel 15 thereby forcing the gas 90 through the exit portion 12 of the inner jacket and also through the elongated slots formed within the central portion, thereby throwing the gases into a divided state and breaking up and suppressing the objectionable noises from the exhaust of engines.

It is obvious from the foregoing construction taken in connection with the drawings that I have provided openings for the escape of the exhaust in the muffler of greater size 100 than the exhaust or intake pipe of the muffler. This will relieve any back pressure of the engine without lessening the power of the same and at the same time give sufficient pressure to revolve the convoluted wheel 105 whereby the rotation of the same will compel the exhaust to escape in the atmosphere in a divided state thereby eliminating the objectionable noises, made by the different gas and steam engines now in use.

It will be seen from the foregoing description that I have constructed a device which

will perform the necessary functions and it is further to be understood that other minor details may be resorted to that come within the scope of the appended claims without departing from the spirit of the present invention.

Having thus fully described my invention what I claim as new and desire to secure by Letters Patent is:

10. 1. A silencer for the exhaust of an engine including an inner perforate sectional casing, an outer concentric casing disposed in spaced relation thereto, a rotatable member disposed within said inner casing, said member having a plurality of spirally arranged parallel uniformly spaced apart blades arranged thereupon, and a bearing arranged upon the interior of each end section of the inner casing, said bearing providing a journal for said rotatable member, as and for the purpose set forth.

2. In a device of the character described, the combination of a pair of concentric casings held in spaced relation, the inner casing thereof being perforate and composed of a plurality of independent casing sections, a rotary member journaled within said inner casing, the said rotary member having a plurality of spirally arranged uniformly spaced apart blades extending from

the periphery thereof, and a bearing arranged within each end section of said inner casing for said rotary member, as and for the purpose set forth.

3. In a device of the character described, the combination of a pair of concentric casings held in spaced relation, the inner casing comprising a plurality of independent and detachably connected casing sections, a rotary member journaled within said inner casing, said inner casing being perforated to communicate with said outer casing, the said rotary member having a plurality of spirally arranged uniformly spaced apart blades extending therefrom, bearings arranged, one within each end section of said inner casing, said bearings providing a journal for said rotary member, an exhaust pipe connected at one end to said inner casing whereby the force of the exhaust gases will impart rotary movement to said rotary member, an outlet pipe connected to said inner casing at the opposite end thereof, said exhaust gases being discharged through both the said perforations and said outlet pipe, as and for the purpose set forth.

ERNEST C. RODWICK.
